FIG. 1

FIG. 3

FIG. 2

FIG. 4

FIG.5

FIG.7

FIG.6

FIG. 1 is a top plan view of the litter receptacle, showing my new design;

FIG. 2 is a front elevational view;

FIG. 3 is a right side elevational view;

FIG. 4 is a fragmentary cross-sectional view taken along the line 4—4 of FIG. 1 and FIG. 5;

FIG. 5 is a top plan view of a litter receptacle, showing a modified form of my new design;

FIG. 6 is a front elevational view thereof; and

FIG. 7 is an edge elevational view taken on line 7—7 of FIG. 5.

In either embodiment of my litter receptacle, the bottom is plain and not ornamental.

This is a continuation-in-part of design application Ser. No. 361,647, filed May 18, 1973, now U.S. Pat. No. D. 233,304, dated Oct. 22, 1974.

I claim:

The ornamental design for a litter receptacle, substantially as shown and described.
